UNITED STATES PATENT OFFICE.

HENRY M. HUGHES, OF ELDON, IOWA.

HARROW-TOOTH FASTENING.

No. 914,278.

Specification of Letters Patent.

Patented March 2, 1909.

Application filed August 21, 1908. Serial No. 449,631.

To all whom it may concern:

Be it known that I, HENRY M. HUGHES, a citizen of the United States of America, and resident of Eldon, Wapello county, 5 Iowa, have invented a new and useful Harrow-Tooth Fastening, of which the following is a specification.

The object of this invention is to provide improved means for securing a harrow tooth.

10 A further object of this invention is to provide an improved bar, tooth and connection for harrows.

15 A further object of this invention is to provide an improved fastening for adjustably supporting and holding a harrow tooth.

20 My invention consists in the construction, arrangement and combination of elements hereinafter set forth, pointed out in my claims and illustrated by the accompanying drawing, in which—

Figure 1 is a plan of a harrow bar to which my improved invention is applied. Fig. 2 is a cross-section on the indicated line 2—2 of Fig. 1. Fig. 3 is a cross-section of the 25 device on the indicated line 3—3 of Fig. 1. Fig. 4 is a perspective of the clamping yoke employed in my improved construction. Fig. 5 is a different perspective of the same device.

30 In the construction of the device as shown, the numerals 10, 11 designate parallel bars relatively thin and wide and of the desired length to reach from end to end of a harrow section. The bars 10, 11 are arranged in 35 pairs slightly spaced apart and one pair may be spaced apart from another pair as desired to produce a harrow section of any desired form. A yoke 12 is mounted on and embraces the bars 10, 11. The yoke 12 is

40 formed with parallel sides, a connecting piece or bottom 12^a integral with said sides and ears 12^b, 12^c extending inward from the upper end portions of the sides parallel with the bottom piece. The ears 12^b, 12^c are

45 formed with notches 13, 14 in vertical alignment with an aperture 15 in the bottom piece 12^a. The aperture 15 and the notches 13, 14 are angular. A harrow tooth 16, angular in cross-section and attenuated or

50 pointed at its lower end, is mounted through the aperture 15 and notches 13, 14. Adjacent end portions of the ears 12^b, 12^c are slightly spaced apart. Ears 12^d are formed on and extend upward from the sides of the

55 yoke 12 adjacent the ears 12^b, 12^c and are formed with apertures 17, 18 in transverse

alignement. A clamping bolt 19 is mounted through the alining apertures 17, 18 in the ears 12^d and a nut 20 is mounted on one end of said bolt. The aperture 17 is angular and 60 the bolt 19 is of the type known as carriage bolt with an angular shank adjacent its head of a size and shape to fit said aperture and prevent rotation of the bolt therein. The body of the clamping bolt 19 is in contact with one side of the harrow tooth 16 and tends to hold said tooth in the notches 13, 14. When the tooth 16 is mounted as shown, the nut 20 may be tightened on the bolt 19 and tend to press the ears 12^d toward each other, thus moving the sides of 65 the yoke 12 toward each other and causing them to clamp tightly on the bars 10, 11 and cause said bars to grip opposite faces of the tooth.

75 It will be observed that the parallel bars 10, 11 hold the tooth against longitudinal movement and against oscillation, while the bolt 19 and the ears 12^b, 12^c hold the tooth against oscillation at right angles thereto or 80 in the plane of the trend of the parallel bars.

The bars may be mounted in series to produce a harrow in any desired manner and may be arranged for oscillation or rotary adjustment with the teeth, to incline the 85 teeth in either direction from the vertical, as desired and such arrangement and adjustment of the bars constitutes no part of my present invention.

I claim as my invention—

90 1. The combination of parallel bars, a yoke embracing said bars, a tooth mounted between said bars and extending through said yoke, and means for contracting said yoke.

95 2. The combination of parallel bars, a yoke mounted on and embracing said bars, said yoke adjustable longitudinally of said bars, a tooth mounted between and transversely of said bars and extending through said yoke, 100 and means for contracting said yoke.

105 3. The combination of parallel bars, a yoke embracing said bars, said yoke formed with an aperture in its lower end and notches in its upper end, a tooth mounted between and transversely of said bars and extending through said aperture and notches, and a clamping bolt and nut connecting the sides of said yoke.

110 4. The combination of parallel bars, a yoke embracing said bars, said yoke formed with an aperture in its lower end portion and

notches in its upper end portion opposite said aperture, said yoke also formed with ears, a clamping bolt extending through said ears and across the yoke, a nut on said 5 clamping bolt, and a tooth mounted through said notches and aperture.

5. The combination of a yoke formed with parallel sides, an end portion connecting said sides, ears extending inward from opposite 10 ends of said sides and spaced apart, the end portion formed with an angular aperture, the ears formed with angular notches, said yoke also formed with outwardly extending ears transversely apertured, one of

the apertures in an outwardly extending ear ¹⁵ being angular, and a clamping bolt adapted to be mounted in said apertures of the outwardly extending ears, a portion of said clamping bolt formed angular in cross-section and fitting said angular aperture in 20 said ear, and a nut on said clamping bolt.

Signed by me at Eldon, Iowa, this 24th day of June, 1907.

HENRY M. HUGHES.
